UNITED STATES PATENT OFFICE.

JACK SCHWAB, OF NEW YORK, N. Y.

DESIGN FOR A BUFFET SCARF.

Application filed August 23, 1926. Serial No. 18,806. Term of patent 3½ years.

To all whom it may concern:

Be it known that I, JACK SCHWAB, a citizen of the United States, residing in New York, county of New York, and State of New York, have invented a new, original, and ornamental Design for a Buffet Scarf, of which the following is a specification, reference being had to the accompanying drawing, forming part thereof, in which the figure is a plan view of a buffet scarf showing my new design.

I claim:

The ornamental design for a buffet scarf as shown.
